AUTOMATIC RECORD CHANGING
TALKING MACHINE

Amédée Nicole, Sainte Croix, and Louis Thévenaz, Les Rasses, near Sainte Croix, Switzerland, assignors to Hermann Thorens Societe Anonyme, Sainte Croix, Switzerland, a firm of Switzerland

Application August 17, 1945, Serial No. 611,000
In Switzerland September 21, 1944

1 Claim. (Cl. 274—10)

1

This invention relates to automatic record changing talking machines and more particularly to talking machines adapted to play successively the upper face of a record supported on the turn table and the lower face of the lowermost record of a stack supported over the turn table by the supporting surface of a vertical shaft passing through the central aperture of the records.

A feature of the invention resides in the fact that the lowermost record of the reserve stack is driven in a direction opposite to the rotation of the turntable by means of the central shaft which is driven by a second motor positioned over the reserve stack and independent from the motor which drives the turntable.

A further feature of the invention resides in the fact that the central shaft is removably supported at each of its extremities, the reserve records being thus loaded on to the shaft before the introduction thereof into its supports.

The accompanying drawings show by way of example one convenient construction embodying the invention and several modifications of the removable shaft.

In the drawings, Figure 1 is a diagrammatical elevation of the automatic record-changing talking machine.

Figure 2 is a plan view thereof.

Figure 3 is an elevation with parts in section on enlarged scale of the removable shaft.

Figs. 4 and 5 are similar views of a modification of the removable shaft in playing position, and in loading position of the records respectively.

Figs. 6 and 7 are similar views of a second modification of the removable shaft in playing position, and in loading position of the records respectively.

Figs. 8 and 9 are similar views of a further modification of the removable shaft in playing position, and in loading position of the records respectively.

Fig. 10 is a sectional view on line X—X of the upper bushing of Fig. 7.

Fig. 11 is a view on line XI—XI of the upper bushing of Fig. 9.

Figs. 12 and 13 relate to a further modification of the removable shaft in playing position, and in loading position respectively.

Fig. 14 is a cross section on line XIV—XIV of Fig. 3.

Referring to Figs. 1 and 2, the reference character 1 designates an electric motor of the phonograph motor standard type fixed on the under-

2

side of the base plate 2 by means of bolts 61 and the shaft of which is designated by 3.

The upper end of the driving shaft 3 is formed with a socket 10 within which is a ball thrust bearing 13 rotatably supporting the semi-spherical lower end 14 of a straight shaft 6 passing through the central aperture of a stack of records 15, the lowermost 15¹ of which is supported on a supporting surface 7.

The talking machine represented in the drawings is adapted to play successively the upper side of the record 5 supported on the turntable 4, the underside of the record 15¹ supported on the supporting surface 7, then the upper side of the record 15¹ after this record has been dropped from the surface 7 onto the turntable by a record feeding device, of any conventional type acting through the central hole of the records, then the underside of the new lowermost record 15² of the stack which has replaced on the surface 7 the record 15¹, and so on until all of the records of the stack have been played on both sides. The turntable 4 is driven, as usually in the clockwise direction and, as is necessary in order to play the underside of standard records from below, the records 15 of the stack supported on surface 7 of shaft 6 are driven in counter-clockwise direction, as shown by the arrows f¹ and f² of Figs. 1 and 14.

30 The rotation of the removable shaft 6 is brought about through the medium of a coupling member provided at the lower end of the driving shaft 79 of a second electric motor 8 positioned over the stack of records 15 and independent from the lower motor 1. This upper motor 8 is also of the phonograph motor standard type; it is fixed on the horizontal base of a bracket 9 the column 9' of which is fastened on the base plate 2 of the machine frame. The shaft 79 is rotatably supported in the base of the bracket 9 and its lower end is formed with a bushing 11 adapted to receive the semi-spherical upper end 84 of the removable shaft 6.

The shaft 6 is removably supported, at its lower end, by the ball thrust bearing 13 within the socket 10 formed at the upper end of the lower driving shaft 3, and at its upper end, by the bushing 11 formed at the lower end of the upper driving shaft 79, which latter is in vertical alignment with the lower driving shaft 3. When so supported in alignment with both the driving shafts 3 and 79, the removable shaft 6 may be rigidly coupled with the upper shaft 79 by means of a pin 12 passing through the bushing 11 and cooperating with a vertical flat surface 99 (Fig.

14) on the semi-spherical upper end 84 of the shaft 6. 13 designates a presser plate adapted to hold the records of the stack in place in order to prevent them to oscillate during the rotation thereof. The upper motor 8 may be with continuous or intermittent running; its running may be for instance interrupted during the playing of the upper face of the record 5 resting on the turntable 4.

As both the socket 10 and the bushing 11 are axially immovable, the upper bushing 11 is provided in the construction shown in Fig. 3 with an axial clearance 14 for the introduction and the withdrawal of the shaft 6. The reserve records are loaded on to the shaft 6 together with the presser plate 13 before the introduction of this shaft into the socket 10 and the bushing 11. The records 15 and the presser plate 13 are first loaded from above onto the shaft 6 after this shaft has been removed from the socket 10 and the bushing 11; the semi-spherical upper end 84 of shaft 6 is then introduced into the bushing 11 and lifted up to the bottom of the recess 14 so as to enable the semi-spherical lower end 74 of the shaft to enter the socket 10; the shaft 6 is then lowered until its semi-spherical lower end 74 comes to lie on the ball thrust bearing 73, and the pin 12 is put into coupling position.

In the modification of Figs. 4 and 5 the lower socket 20 is provided with a spring urged thrust plate 22 which permits to bring the shaft 6 into playing position by pushing it down against this spring urged thrust plate as shown in Fig. 5.

In the modification of Figs. 6, 7 and 10 the upper bushing 31 is provided with a radial passage 32 through which the upper semi-spherical extremity of the shaft 6 may be introduced from the side as shown in Fig. 7. Two spring urged pins 33 hold the shaft in place after its introduction through the passage 32. The lower semi-spherical end 74 of the shaft 6 is rotatably supported within the socket 10 by the ball thrust bearing 73.

In the construction of Figs. 8, 9 and 11, the upper bushing 41 is provided with a radial passage 42 and the lower socket 20 is provided with a spring urged thrust plate 22.

In the construction of Figs. 12 and 13 the upper bushing is constituted by a sleeve 51 slidingly mounted on the hollow axle 52 so as to cap the upper semi-spherical end 84 of the shaft 6 after the latter has been brought in axial position. The lower end 74 of shaft 6 is rotatably supported within the socket 10 by the ball thrust bearing 73.

It is to be understood that the removably supported shaft construction may be applied to record-changing talking machines in which the central record feeding shaft does not rotate or in which this shaft is formed as a cranked shaft.

However the fact that the support of the upper bushing does not need to be displaced for the record-loading operation permits to use a statically more stable fixed stand for supporting this upper bearing thus obtaining an exact centration of the shaft which is particularly advantageous if the shaft should rotate.

What we claim is:

In an automatic record-changing talking machine adapted to play successively the underside of the lowermost record of a stack supported on first rotatable supporting means driven by a first vertical shaft and the upper side of the same record after being dropped without reversal onto second rotatable supporting means driven by a second vertical shaft situated underneath and in alignment with the first vertical shaft, a frame, first bearing means for said first vertical shaft fixedly secured to said frame, second bearing means for said second vertical shaft fixedly secured to said frame, a removable shaft adapted to fit in the playing position of the talking machine, between the adjacent extremities of said two vertical shafts, and in alignment with them, semi-spherical members at both ends of said removable shaft, a thrust ball bearing at the upper end of said second vertical shaft, for the lower semi-spherical member of said removable shaft, a coupling member at the lower end of said first vertical shaft provided with a recess adapted to engage the upper semi-spherical member of said removable shaft, the depth of said recess over said semi-spherical member being at least equal to the length of the lower portion of said removable shaft engaged in said thrust bearing when said removable shaft is in position for the playing of the records, so as to allow the removal of said removable shaft from said position without displacing any of said bearing means and to permit the lateral introduction of the records to be played between the adjacent extremities of said two vertical shafts.
